(57) **CLAIM**

The ornamental design for a tyre, as shown and described.

DESCRIPTION

FIG. 1 is a front elevational view of a tyre showing my new design, the rear elevational view being a mirror image thereof;

FIG. 2 is a left side view thereof, the right side view being a mirror image thereof;

FIG. 3 is a perspective view thereof; and,

FIG. 4 is an enlarged fragmentary front elevational view thereof.

1 Claim, 4 Drawing Sheets
